UNITED STATES PATENT OFFICE.

CHARLES F. KURZ, OF CLEVELAND, OHIO.

DESIGN FOR A DISPLAY-CASE FOR PHARMACIES.

48,640.

Specification for Design.

Patented Feb. 29, 1916.

Application filed December 13, 1915. Serial No. 66,631. Term of patent 7 years.

To all whom it may concern:

Be it known that I, CHARLES F. KURZ, a citizen of the United States of America, residing at Cleveland, in the county of Cuyahoga and State of Ohio, have invented a new, original, and ornamental Design for Display-Cases for Pharmacies, of which the following is a specification, reference being had to the accompanying drawing, forming part thereof.

The figure is a perspective view of a display case showing my new design.

I claim:

The ornamental design for a display case, as shown.

CHARLES F. KURZ.

Witnesses:

B. C. BROWN,
V. C. LYNCH.
